Fig. 2.

UNITED STATES PATENT OFFICE.

WALTER S. DUWELIUS, OF CINCINNATI, OHIO.

DEVICE FOR APPLYING PRESSURE.

1,149,037.

Specification of Letters Patent.

Patented Aug. 3, 1915.

Application filed October 12, 1914. Serial No. 866,299.

To all whom it may concern:

Be it known that I, WALTER S. DUWELIUS, a citizen of the United States, residing at Cincinnati, county of Hamilton, State of Ohio, have invented certain new and useful Improvements in Devices for Applying Pressure; and I do hereby declare the following to be a full, clear, and exact description of the invention, such as will enable others skilled in the art to which it appertains to make and use the same.

This invention relates to devices for applying pressure and is adapted for use in connection with various forms of clamping devices, such as vises, chucks, quoins and the like.

The invention is directed to the provision of a pressure-applying device so constructed that it will adapt itself automatically for equalization or for a desired distribution of pressure along the length of the device.

While my invention is adapted for use in connection with clamping devices varying widely in their construction and in the relations in which they are used, it is of special utility in connection with printing apparatus either as a quoin or as a spacing member used in combination with a quoin to lock a form of type in a chase.

The invention involves the provision of a pressure-applying device having a plurality of contact members distributed along the length of the device and means for causing a differential, lateral movement of these contact members whereby they will be brought to bear upon a coacting surface with equal pressure or with pressure varying in a predetermined degree.

In accordance with the preferred embodiment of the invention, the pressure device consists of a frame having a plurality of contact members therein, each of which presents a curved surface, these members being adapted to be moved laterally so that some or all of them are projected more or less from the side of the frame into engagement with the coating surface. When constructed in the form of a quoin, the frame is preferably of tubular form, rectangular in cross-section and having one side or two opposite sides cut away to permit of projecting the contact members located within the frame through the sides of the frame.

The contact members are preferably in the form of balls or rollers of such size and number that when they are in substantial

alignment lengthwise of the device, they extend practically from one end to the other thereof.

At one or both ends of the device, means are provided for subjecting the contact members to pressure in the direction of the length of the device so as to cause them, or certain of them, to be projected laterally through an open side of the device into contact with a surface extending substantially parallel to the device.

With this form of pressure-applying device, the several contact members will move outwardly to such extent as is necessary to cause them to engage the co-acting surface whether the latter be exactly parallel to the pressure-applying device or not. This characteristic makes the device of special value as a quoin or piece of furniture for use in connection with a chase which has become slightly sprung. Also, the several contact members may be caused to move so as to equalize the pressure thereof upon the coacting surface. But if it be desired that the pressure of the several contact members be distributed unequally, this may be readily accomplished by merely varying the curvature of the surfaces of the several contact members so that certain of them will be subjected to greater lateral pressure than others. In this way, the device may be made to relieve the pressure over portions of the coacting element which are structurally weak.

The invention will be better understood by reference to the following description taken in connection with the accompanying drawings in which Figure 1 is a plan view of the pressure-applying device; Fig. 2 is a side view of the same broken away and sectioned in part; Fig. 3 is a transverse section of the device; Fig. 4 is a view similar to Fig. 1 illustrating a slight modification and showing the device employed as a quoin; Fig. 5 is a view similar to Fig. 1 illustrating a further modification and Fig. 6 is a transverse section of the device shown in Fig. 5.

Referring to these drawings, the device consists of a tubular frame or casing 7 of rectangular cross-section. On one side, this casing is cut away, the cut-away portion being of such width as to leave flanges 8 projecting toward each other and serving as a retaining means for the contact members. These contact members are provided with

coacting, curved surfaces; they may be in the form of rollers, balls, ovals or other form as desired. In the present instance, cylindrical contact members in the form of 5 rollers 9 and 10 are shown. The rollers 10 are of such size that they are at all times retained within the casing 7, these rollers being of greater height than the distance between the flanges 8. The rollers 9, however, 10 are of less height and can be projected through the space between the flanges 8. These rollers 9 have axially disposed pins 11 at their ends which are adapted to engage the flanges 8 to prevent the rollers 15 from being moved entirely out of the casing 7.

The rollers 9 and 10 are alternated throughout the length of the casing 7 as shown in Figs. 1 and 2. At one end of the 20 casing, means are provided for subjecting the entire series of contact members to pressure in the direction of the length of the casing 7. This consists of a screw 12 threaded into an opening in the end of the casing 25 7 and having a polygonal head outside the casing. The end of the screw 12 engages a bearing block 13 provided with a curved face to coact with the end roller 10.

With this form of pressure-applying device, the screw 12 may be screwed up so as to subject the rollers 9 and 10 to pressure in the direction of the length of the device and thus cause the alternate rollers 9 to be projected laterally through the opening in 30 the side of the casing 7 as shown in Fig. 1. The contact members 9 will thus be caused to move laterally into engagement with a coacting surface and to engage that surface with the desired degree of pressure. If that 35 surface be parallel to the device, all of the rollers 9 will be projected laterally the same amount and will exert equal pressure upon the surface. If the surface be out of parallelism with the device, certain of the contact 40 members 9 will move laterally to a greater extent than others, and if all of them be of the same diameter as shown in Fig. 1, they 45 will exert substantially equal pressure upon the surface.

50 In Fig. 4, the device is shown as a quoin employed in a chase 14 for locking a form of type 15 therein. In this figure, the chase 14 is shown as having one side slightly sprung so that the inner wall of that side is 55 not exactly parallel to the quoin. Because of this, certain of the contact members 9 are shown as having been projected laterally to a greater extent than others to compensate for the variation in the distance between 60 the quoin and the wall of the chase at different points along the length of the quoin. Also, in Fig. 4, certain of the contact members 9 are shown as of greater diameter than others. These contact members of greater 65 diameter will be subjected to lateral pres-

sure to a less degree than those of smaller diameter. They are, therefore, located at such points that they will engage the portions of the chase which are relatively weak so that at those portions, the chase will be 70 subjected to a lower degree of pressure. Thus, instead of equalizing the pressure throughout the length of the device, the provision of such contact members 9 differing in diameter serves to distribute the pressure 75 unequally in the desired manner.

In Fig. 5, a construction is shown differing from that illustrated in the other figures in that the casing of the device is cut away on opposite sides and all, or practically all, 80 of the rollers are arranged for lateral movement, some of them being projected on one side of the casing and the others on the opposite side. All of the rollers 16, except the one 17 at the end of the series, are of 85 such height that they will pass between the flanges 8 of the cut-away sides of the casing 7, and they are provided with axial pins 11 which coact with the flanges 8 as retainers. When pressure is applied to the series 90 of rollers by means of the screw 12, alternate rollers 16 will be projected on one side and the others on the opposite side of the device into contact with the elements lying 95 on opposite sides of the casing.

When employing the invention in quoins for use with type-forms, I prefer to use two quoins in each chase, one open on one side as in Figs. 1 to 4 and the other open on both sides as in Figs. 5 and 6.

100 It will be noted that while pressure members in the form of disks are shown in the drawings, the construction in this respect may be varied, as for instance, by using members which are oblong with semi-circular 105 engaging surfaces at their ends.

What I claim is:

1. A device for applying pressure comprising a hollow frame-member slotted lengthwise thereof, a plurality of contacting devices arranged in line within the frame-member, and means operable from outside the frame-member for moving the contacting devices in the direction of the length of the frame-member, said devices 115 being so shaped that when moved in the direction of the length of the frame-member, certain of them are caused to project through said slotted opening in the frame-member; substantially as described.

120 2. A device for applying pressure comprising a hollow frame-member of rectangular cross-section closed at its ends and slotted lengthwise of the member along one side, a plurality of contacting devices arranged in line within the frame-member, and a threaded member operable from the exterior of the frame-member to cause movement of said devices lengthwise of the frame-member, said contacting devices be- 125 130

ing so shaped that when they are so moved, certain of them are caused to project through said slotted opening in the frame-member; substantially as described.

5 3. A device for applying pressure comprising a hollow frame-member slotted lengthwise thereof, a plurality of contacting devices arranged in line within the frame-member, means operable from outside the frame-member for moving the contacting devices in the direction of the length of the frame-member, said devices being so shaped that when moved in the direction of the length of the frame-member, certain of them are caused to project partially through said slotted opening in the frame-member, and means for limiting the movement of the contacting devices through said opening; substantially as described.

20 4. A device for applying pressure comprising a hollow frame-member of rectangular cross-section closed at its ends and having a slotted opening extending lengthwise of the member in one of the sides of the member, which opening is of less width than the width of the space within the hollow frame-member, a plurality of contacting devices arranged in line within the frame-member, and a threaded member operable from the exterior of the frame-member to cause movement of said devices lengthwise of the frame-member, said contacting devices being so formed that when they are so moved, certain of them are projected partially but not entirely through the said slotted opening in the frame-member; substantially as described.

25 5. A device for applying pressure comprising a casing of rectangular cross-section open along one side and having retaining flanges at said open side, a plurality of movable members lying within the casing and disposed in substantial alinement length-

wise thereof, and a screw operable from outside the casing for subjecting said members to pressure lengthwise of the casing, said members being so formed that when they are subjected to pressure by the screw, certain of them are moved laterally to cause them to project through the opening in the side of the casing; substantially as described.

6 6. A device for applying pressure comprising a casing of rectangular cross-section having lengthwise openings in opposite sides thereof, a plurality of movable members lying within the casing and disposed in substantial alinement lengthwise thereof, and a screw operable from outside the casing for subjecting said members to pressure in the direction of the length of the casing, said members being so shaped that when subjected to pressure by the screw, they are moved laterally so that some of them are projected through the opening in one side of the casing and some of them through the opening in the opposite side; substantially as described.

7 7. A device for applying pressure comprising a casing of rectangular cross-section having a lengthwise opening in one side thereof, a plurality of movable members within the casing of circular form and of different diameters and a screw operable from outside the casing for subjecting the members to pressure lengthwise of the casing whereby certain of the members are moved laterally into positions in which they project through the open side of the casing; substantially as described.

In testimony whereof I affix my signature, in presence of two witnesses.
